UNITED STATES PATENT OFFICE.

ALBION L. F. MITCHELL, OF LYNN, MASSACHUSETTS, ASSIGNOR TO THE MITCHELL HEEL AND EDGE BURNISHING COMPANY, OF KITTERY, ME.

HEEL-BURNISHING MACHINE.

SPECIFICATION forming part of Letters Patent No. 312,573, dated February 17, 1885.

Application filed December 30, 1884. (No model.)

To all whom it may concern:

Be it known that I, ALBION L. F. MITCHELL, of Lynn, in the county of Essex and State of Massachusetts, have invented certain 5 Improvements in Heel-Burnishing Machines, of which the following is a specification.

This invention, which is an improvement on that shown in my Patent No. 310,532, of January 6, 1885, has for its object to provide 10 a jack adapted both to oscillate a boot or shoe held by it while the heel of said boot or shoe is presented to a burnishing-tool, and also to automatically move the heel so as to present different portions of its edge successively to 15 the burnishing-tool until the entire surface is burnished.

The invention also has for its object to provide a locking device or detent whereby the jack may be held away from the burnishing- 20 tool.

To these ends the invention consists in the several improvements hereinafter described and claimed.

Of the accompanying drawings, forming a 25 part of this specification, Figure 1 represents a front elevation of a jack embodying my invention applied to a burnishing-machine. Fig. 2 represents an end elevation of the same. Fig. 3 represents a section on line $x-x$, Fig. 30 1. Figs. 4 and 5 represent a modification. Figs. 6 and 7 represent detail views.

The same letters of reference indicate the same parts in all the figures.

In the drawings, a represents the standard 35 which supports the arbor of a rotary burnishing-wheel, b , formed to burnish a boot or shoe heel.

To the standard a is rigidly attached a stout arm, c , and to the outer end of this arm is connected 40 by a pivot-bolt, d , a yoke or bearing, e , adapted to oscillate freely on the pivot d .

An arbor, f , is journaled in the yoke or bearing e , and on said arbor is mounted the supporting-frame g of the jack, said frame having bearings h , through which the arbor passes. The frame can therefore oscillate in 45 two directions—viz., with the yoke e and arbor f on the pivot d , and independently of said yoke on the arbor f , at right angles to the

direction in which it is capable of oscillating 50 on said pivot.

The boot or shoe is clamped between the rocking arbor i and rod l in the manner described in my above-named application, said arbor and rod being journaled in bearings in 55 the upper end of the frame g and rocked with the boot or shoe by means of a pinion, h' , on a sleeve rigidly attached to the arbor i , and a rack-segment, i' , on the upper end of the lever j' , which is oscillated by an eccentric 60 wrist-pin, m' , on a disk on the arbor f , said pin entering a slot in the lower end of the lever j' . The arbor i and rod l are so located with reference to the burnishing-wheel b that the heel held between their ends may 65 bear against said wheel. The oscillations of the frame g on the arbor f enable the heel to move toward and from the burnishing-wheel and enable the frame g to move as required when the heel is rotating and is in contact with the wheel. The oscillations of the frame g and the yoke or bearing e on the pivot 70 d enable the heel to be moved across the perimeter of the wheel, so that all portions of the heel-edge may be presented to the burnishing portion of the wheel, as described in my former application. The frame g is connected to the standard by the sliding telescopic connection shown in my former application—viz., a socket, w , fitted to slide on a curved 75 guide-rod, u , rigidly attached to the standard, and a curved rod, a' , secured to the frame g and sliding into and out of the socket w . A spring, f' , secured at one end to the sliding socket w and at the other end to the standard 80 a , pulls the frame toward the burnishing-wheel, as in my former application.

In carrying out my present invention, instead of leaving the frame g free to be oscillated toward and from the standard a on the pivot d by the operator, I provide means whereby said frame is oscillated automatically to a sufficient extent to present all parts of the heel-edge to the burnishing-tool. Said means consist of an arbor, A , journaled in the frame g , 85 and having at one end a disk, B , and at the other end a worm-wheel, C , a connecting-rod, D , eccentrically pivoted at one end to the disk

B, and pivoted at the other end to the socket *w*, an arbor, E, journaled in bearings on the frame *g*, and arranged at right angles to the arbor A, and a worm, F, on said arbor meshing 5 with the worm-wheel C. The arbor E is provided with a series of pulleys, H, of different diameters, one of which is connected by a belt, J, to one of a similar series of pulleys, I, on the arbor *f*. The rotation thus imparted to 10 the arbor E is communicated by the worm F and worm-wheel C to the arbor A, and the eccentric wrist-pin L is thus caused to act on the connecting-rod D, so as to oscillate the frame *g* toward and from the standard *a*, thus causing 15 the heel to move across the tool in the manner required to present all parts of its edge to the tool *b*. The length of the oscillating movements thus imparted to the frame *g* may be varied by adjusting the wrist-pin 20 toward or from the center of the disk B, a slot being provided in the disk in which the wrist-pin is adjustable. The movements of the jack may thus be made to conform to the height of the heel. The connecting-rod D is composed 25 of two sections, 2 3, the one having a right and the other a left hand screw-thread, and a nut, 4, tapped to receive said sections. By turning the nut, the connecting-rod may be lengthened or shortened, to adjust the frame *g* toward 30 and from the standard *a*, and thus determine the distance of the frame from the standard at the two extremes of the automatic oscillating movement.

The rapidity of the oscillating movements 35 may be varied by means of the different-sized pulleys H and I.

It will be seen that the described automatic oscillation of the jack relieves the operator from all labor excepting the act of applying 40 and removing the boot or shoe, the presentation of the heel to the tool being entirely automatic.

The operation of the jack may be stopped 45 when any part of the heel-edge is presented to the burnishing-tool, and the same part of the next heel-edge applied will be first presented to the tool, so that the burnishing action will commence at said point and progress from it 50 across the heel-edge and back.

The base or sleeve *w* of the socket *w*, that 55 slides on the rod *u*, is provided with a spring catch or dog, P, that engages automatically with a notch cut in the rod *u* (see Fig. 5) when the frame *g* is moved away from the burnishing-tool, and thus holds the frame while the operator is removing and applying the work.

The socket *w* may be formed in one piece 60 with the sleeve *w*', as shown in Fig. 3, or may be in a separate piece, pivoted thereto at *x*', as 65 shown in Fig. 4, and as shown in section in Fig. 5.

I claim—

1. The combination, with the burnishing-tool, of the jack pivoted to swing universally, 65 as described, and provided with oscillatory heel-clamping devices, substantially as de-

scribed, mechanism, substantially as described, whereby said clamping devices may be oscillated while the heel held thereby is being presented to the burnishing-tool, and mechanism, substantially as described, whereby the jack is automatically oscillated to present different portions of the heel-edge to the burnishing-tool, as set forth. 70

2. In a heel-burnishing machine, the combination of a supporting-standard, a burnishing-tool mounted thereon, a frame pivoted to said standard to swing universally, heel-clamping devices, substantially as described, mounted in the swinging end of said frame, mechanism, substantially as described, whereby said heel-clamping devices are oscillated, and mechanism, substantially as described, whereby the frame is oscillated automatically to present different portions of the heel-edge to the 80 burnishing-tool, as set forth. 85

3. The jack composed of the yoke or bearing *e*, pivoted to a fixed support to swing in a given plane, the frame *g*, pivoted to the yoke to swing in a plane at right angles to that in 90 which the yoke swings, heel-clamping devices, substantially as described, mounted on the swinging end of said frame, and mechanism, substantially as described, whereby said heel-clamping devices are oscillated, combined with 95 mechanism, substantially as described, whereby the frame is oscillated automatically, as set forth.

4. The combination of a supporting-standard, a burnishing-tool mounted thereon, a frame, *g*, pivoted to said standard to swing universally, heel-clamping devices, substantially as described, mounted in the swinging end of said frame, mechanism, substantially as described, whereby said heel-clamping devices are oscillated, the socket *w*, mounted to slide on a guide on the supporting-standard, the rotating arbor A, journaled in the frame *g*, and the connecting-rod D, connected to the socket *w* and to a disk on the arbor A, as set 100 forth. 105

5. The combination of the standard *a*, having the guide-rod *u*, the sliding socket on said rod, the swinging frame *g*, having the rotating arbor A, and the connecting-rod D, connected 115 at one end to the sliding socket, and adjustably connected at the other end to a disk on the arbor A, as set forth.

6. The combination of the frame *g*, the sliding sleeve *w*, the rotating arbor A, and the connecting-rod adjustable as to the length, as set forth. 120

7. The combination of the standard *a*, having the guide-rod *u*, the frame *g*, having the arbor A, the connecting-rod D, connecting said 125 arbor to a sliding sleeve on said guide-rod, the arbor E on said frame, connected, as described, to the arbor A, and provided with a series of pulleys, H, the arbor *f*, having the series of pulleys I, and a connecting-belt, J, as set forth. 130

8. The combination of the standard having the burnishing-tool and the guide-rod, the jack

pivoted to swing in two directions, as described, the telescopic connection mounted to slide on the guide-rod, and the spring f' , whereby the jack is pulled toward the burnish-

5 ing-tool, the spring-dog on the telescopic connection, and a notch in the guide-rod, whereby the jack may be held away from the burnishing-tool, as set forth.

In testimony whereof I have signed my name to this specification, in the presence of two sub-
scribing witnesses, this 26th day of December, 1884.
